UNITED STATES PATENT OFFICE

92,221

DESIGN FOR A HOUSING FOR COIN CONTROLLED MECHANISM

Everett Worthington, Chicago, Ill., assignor to
Coca-Cola Company, Atlanta, Ga., a corpora-
tion of Delaware

Application March 2, 1934, Serial No. 50,917

Term of patent 14 years

To all whom it may concern:

Be it known that I, EVERETT WORTHINGTON, re-
siding at Chicago, in the county of Cook and State
of Illinois, have invented a new, original, and or-
namental Design for a Housing for Coin Con-
trolled Mechanism, of which the following is a
specification, reference being had to the accom-
panying drawing, forming part thereof.

Figure 1 is a front elevation of a housing for

coin controlled mechanism, showing my new de-
sign.

Figure 2 is a top plan view, and
Figure 3 is a side elevation thereof.

I claim:

The ornamental design for a housing for coin
controlled mechanism as shown.

EVERETT WORTHINGTON.
